(57) **CLAIM**

The ornamental design for a decanting device, as shown and described.

DESCRIPTION

FIG. 1 is a perspective view of a decanting device showing the new design;

FIG. 2 is a front view thereof;

FIG. 3 is a partial enlarged view at part A thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dot-dash broken lines in FIG. 3 define the bounds of the claim and form no part of the claimed design.
